UNITED STATES PATENT OFFICE.

HAROLD K. SMITH, OF CHICAGO, ILLINOIS.

UNLOADING AND RECLAIMING ELEVATOR.

Application filed August 24, 1921. Serial No. 495,075.

To all whom it may concern:

Be it known that I, HAROLD K. SMITH, a citizen of the United States, residing at Chicago, county of Cook, and State of Illinois, 5 have invented a certain new and useful Unloading and Reclaiming Elevator, of which the following is a specification.

My invention relates more particularly to a new and useful elevator intended and 10 adapted for unloading bulk material such as coal, ore, crushed stone, etc., from boats, barges, railroad cars, trucks and the like and delivering it to cars, boats, trucks, storage pile, pit or bins, and to reclaim such material from the storage pile, pit or bins and 15 reload into boats, barges, railroad cars and the like, as desired.

It is the object of my invention to provide an apparatus of this class which unloads or 20 reclaims continuously while in operation rather than intermittently, as with the forms now on the market, and thereby afford a much greater capacity than any of the forms now in use. With the forms now in general 25 use, one large bucket supported by machinery of enormous weight travels back and forth and up and down with every bucket of material; there is a very decided disadvantage in this construction for it necessarily 30 calls for large and expensive motors to take care of the high power peaks coincident upon acceleration and deceleration with a large mass of moving parts, whereas with my invention, by eliminating entirely such 35 parts much smaller and cheaper motors can and will produce a very much larger capacity.

Another object of my invention is to provide a device of this class with digging 40 means so designed as to positively and automatically feed into the material being moved, that is, being unloaded or reclaimed.

A further object is to provide a device of 45 this class which is easily operated and calls for comparatively little attention when in operation.

Another object of my invention is to provide a device of this class which is equally well adapted for unloading or reclaiming.

50 The above and other features of novelty, advantage and capabilities will become apparent from the detailed description of the accompanying drawings in which I have illustrated an unloading and reclaiming elevator embodying one form of my invention, but the construction there shown is to be

understood as illustrative only and not as defining the limits of my invention.

Figure 1 is an elevational view of a device embodying one form of my invention showing it applied to a travelling bridge, a portion of the bridge being broken away. 60

Figure 2 is an enlarged elevational view of the same, partly in section.

Figure 3 is a vertical sectional view taken 65 on the line 3—3 of Figure 2 and looking in the direction indicated by the arrows.

Figure 4 is a horizontal sectional view taken on the line 4—4 of Figure 2.

Figure 5 is a horizontal sectional view 70 taken on line 5—5 of Figure 2.

Figure 6 is a sectional view taken on the line 6—6 of Figure 2.

Figure 7 is an enlarged elevational view partly in section, of a similar device 75 embodying a modified form of the feeding mechanism.

Figure 8 is a vertical sectional view taken on the line 8—8 of Figure 7.

Figure 9 is a horizontal sectional view 80 taken on the line 9—9 of Figure 7.

In general, the structure shown as embodying my invention, consists of two or more opposed digging bucket elevators pivoted about their respective head shafts to a 85 head piece structure, which in turn is suspended by means of a cable from a main carriage mounted on a suitable traveling bridge or tower, with a variably inclined endless conveyor or conveyors connecting with 90 a hopper suspended from an auxiliary carriage on the traveling bridge, designed and adapted to carry the material from the head piece to the point of deposit and motors, through suitable operative means, for raising and lowering the entire mechanism and for operating the bucket conveyors and forcing them to gradually feed toward each other and dig into the material being moved. 95

While my invention illustrated by the accompanying drawings, is shown applied to a traveling bridge, it is, of course, to be understood that it may be applied to a stationary bridge, or other superstructure. However, referring to the drawings in detail, the 100 traveling bridge is indicated as a whole by the reference character 10, which bridge is provided with the usual legs equipped with suitable motor driven trucks for traveling on the tracks as shown. The bridge 10 is 105 provided with a swinging boom 11, which boom may be raised or lowered in the cus-

tomary way through the cable 12 operated by a motor in the operator's cab 13. The swinging boom as also the bridge, is provided with the usual track or rails. Mounted to travel on the swinging boom is a main carriage 14 electrically driven. Suspended from the main carriage by means of a cable 15 is a head piece 16, which head piece and its attached parts hereinafter to be described 10 may be raised or lowered as desired through the cable 15 by means of a suitable electric motor 17 mounted on the main carriage and operatively connected to the drum 18 through suitable gears as best shown in dotted line in Figure 1.

Pivottally connected to the head piece near its inner lower portion is a variably inclined endless conveyor 19 which conveyor is at its opposite end pivottally connected to the hopper 20 per 20. The hopper 20 is suspended by means of a suitable cable from the auxiliary carriage 21 in such a manner as to be raised and lowered as desired by an electric motor or other suitable means not shown. The auxiliary carriage is designed and adapted to travel back and forth on the bridge as desired. Mounted in the frame work of the bridge is a horizontal endless conveyor 22 for carrying away the material discharged 30 thereon from the hopper 20.

The head piece 16 is provided with sides, ends and top, and in this respect may be termed a housing. Pivottally mounted on the head shafts 24 and 25 in the head piece 16 35 are two endless bucket conveyors 26 and 27 which travel over comparatively small gears 28 and 29 fast to their respective shafts, while their opposite ends travel over idlers 30 and 31 rotatably mounted within the casings 32 near the lower ends thereof, the upper ends of said casings are pivottally mounted on their respective head shafts as best shown in Figure 2.

Mounted in the upper portion of the head piece 16 on the supporting member 33 is a main motor 34 for driving the bucket conveyors 26 and 27. These conveyors are operatively connected to the main motor through the following gear arrangement. 50 The armature of the motor 34 is provided with a small gear 35 which gear is in mesh with and drives a comparatively large gear 36 fast on a stub shaft rotatably mounted in the bearing 37 which stub shaft carries on 55 its outer end a comparatively small gear 38 which small gear is in mesh with and drives a comparatively large gear 39 on the head shaft 24. The gear 39 is in mesh with and drives a similar gear 40 on the head shaft 25.

60 From this it will be seen that when the motor is operated, it will, through the gear arrangement just described, drive the bucket conveyors in the proper direction and cause them to pick up the material desired to be 65 moved on their upward travel and that they

are traveling upwardly on the inside instead of the outside. The latter feature is desirable, not only because it insures better loading of the buckets, but it also eliminates entirely any possibility of the buckets digging 70 or ripping into the side of the boat, bin or other vessel from which the material is being moved. The material is carried upwardly on the inside of the conveyors by means of the buckets and over the upper 75 ends from where it is thrown out as the buckets come around on to a two-way deflector or chute 41, down which it slides to two horizontal endless conveyors 42 and 43 positioned on either side of the bucket conveyors within the head piece 16. The endless conveyors 42 and 43 travel over the rollers fixed to shafts 44 and 45 rotatably mounted in the head piece 16. The shaft 44 is provided with a small sprocket 46 which 80 is driven by a sprocket 47 on the head shaft 25 through the sprocket chain 48. The conveyors 42 and 43 travel from left to right and thus convey the material to the inner lower edge of the head piece 16 where it is 85 dumped into a chute 49 and carried thereby down on to the variably inclined conveyor 19 by means of which it is carried to the hopper 20 and discharged therefrom on to the horizontal conveyor 22 and taken away 90 to the desired place.

In order to positively cause the conveyors to feed at all times gradually into the material being moved and thus insure the buckets being properly loaded to their capacity I 100 have provided a feeding mechanism. Two modifications being illustrated in the accompanying drawings I will now describe the preferred form. Within the head piece 16 there is mounted on the supporting member 33 an auxiliary motor 50 which might correctly be termed a feeding motor as it 105 operates the feeding mechanism. Fast to the armature of this auxiliary motor is a small gear 51 which in turn is in mesh with 110 and drives a comparatively large gear 52 fast to a shaft rotatably mounted in the bracket or bearing 52 which shaft on its opposite end is provided with a comparatively 115 small gear 53 which is in mesh with and drives a comparatively large gear 54 fixed to the shaft 55 mounted in the bearing 56. The shaft 55 has fixed thereto by any suitable means, near its ends, beveled gears 57 which gears are in mesh with and drive the 120 beveled gears 58 fixed to the upper end of the shafts 59. The shafts 59 extend downwardly as best shown in Figures 1, 2 and 3 to a point about intermediate the ends of the conveyor casings. The shafts 59 are at 125 their lower ends provided with a worm screw 60 which screw is in mesh with and drives the worm wheels 61 fixed to the screw threaded shafts 62 which shafts near each end thereof passes through and co-operates 130

with screw threaded lugs or brackets 63 which lugs or brackets are secured to the conveyor casings on each side thereof by any suitable means, as by the bolts, best shown 5 in Figure 6. Through this feeding mechanism it will be readily seen that the two bucket conveyors are caused to positively and gradually feed into the material as it is carried away. In other words, during 10 the main movement of the buckets upwardly they are being forced slightly but positively into the material and toward each other as the conveyor operation is carried on. This feature is highly desirable for with it material 15 can be removed from bins, boats and other vessels without the necessity of manually moving the material from different points to the foot of the elevator so that it can be picked up. With my invention the 20 material is forced from the sides and ends, toward the center so that it can be picked up and carried away. By reversing the motor the conveyors are moved away from each other.

25 In describing my invention thus far, particularly as illustrated in the accompanying drawings, I have referred in detail to the gearing arrangement for operating the feeding mechanism. I shall now describe the 30 other form which is operated through cables and best illustrated in Figures 7, 8, and 9. The same auxiliary motor 50 is utilized. The small gear 51 on the armature of the motor is in mesh with and drives a comparatively large gear 64 fixed to the shaft 65 which shaft is rotatably mounted at one end in one side of the head piece 16 and at its opposite end in the bearing or bracket 66 which bracket is mounted on the supporting 40 member 33 within the head piece 16. The shaft 65 has fixed thereto between the bracket 66 and the large gear 64, a comparatively small gear 67 which small gear is in mesh with and drives a comparatively large 45 gear 68 fixed to the drum shaft 69 which drum shaft is rotatably mounted in bearings fixed to the head piece 16 in the inner upper portion thereof. On the shaft 69 is fixed thereto four drums, 70, 71, 72 and 73. Each 50 of the drums 70 and 73 are provided with separate cables designed to be wound and unwound therefrom, which cables leave their respective drums from the upper side and pass over suitable sheaves 74 rotatably 55 mounted within the head piece 16 on the supporting member 33, thence downwardly under the sheaves 75 on the right hand conveyor casing 32 thence across and around the sheaves 76 on the opposite conveyor casing, thence across and around the sheave 60 75 back to the opposite casing where they are secured by any suitable means, such for example as the loop or eye shown. When the motor is operating in one 65 direction the cables are caused to wind on

the drums 70 and 73, thus forcing the bucket conveyors gradually and positively toward each other and into the material being moved. For drawing the conveyors apart, whenever it is desired,—for instance, starting to remove a new pile or for any other reason, I have provided the drums 71 and 72 with suitable cables. The cables from the drums 71 and 72 pass over the sheaves 77 thence downwardly between the rollers 78 70 75 around the pulleys 79, anchored to the casings 32, up over the pulley 80 and back to the eye 81 where they are anchored. The cable from the drum 72 leaves the drum from the under side while the cable from the drum 71 leaves from the upper side. From this arrangement it will be readily seen that all that is necessary when it is desired to move the bucket conveyors apart is to reverse the auxiliary motor whereupon the releasing cables are wound on their respective drums while the feeding cables are unwound. Likewise, when the conveyors are being forced together for the purpose of causing the buckets to dig into the material the feeding cables are being wound on their respective drums, while at the same time the releasing cables are being unwound. The motors, if desired, may be controlled through 85 any suitable arrangement by the operator in 90 the cab on the bridge. Within the head piece 16 are provided adjacent the endless conveyors 42 and 43 upstanding guards 82 to keep the material on the conveyors and away from the gearing and other parts of 95 100 the apparatus.

Having thus described my invention, I claim

1. In a device of the class described, the combination of plurality of opposed bucket 105 conveyors and positive means for drawing said conveyors toward and from each other, substantially as and for the purposes set forth.

2. In a device of the class described, the combination of a supporting structure, a member suspended therefrom, a plurality of opposed conveyors pivotally mounted on said member and positive means for drawing said conveyors toward and from each 110 115 other.

3. In a device of the class described, the combination of a superstructure, a carriage designed to travel thereon, a member suspended therefrom, a plurality of opposed 120 conveyors pivotally mounted in said member, means for raising and lowering said member and means for drawing said conveyors toward and from each other.

4. In a device of the class described, the combination of a head piece adapted to be 125 adjustably suspended from a superstructure, a plurality of conveyors pivotally connected to said head piece, a motor mounted in said head piece and operatively connected with 130

said conveyors for driving the same, an auxiliary motor mounted in said head piece, and operatively connected in a manner to draw said conveyors to and from each other and means within said head piece for carrying the material from said conveyors to a discharging point.

5. In a device of the class described, the combination of a bridge, a carriage designed to travel thereon, a vertically adjustable head piece suspended from said traveling carriage, a motor on said carriage for raising and lowering said head piece, a plurality of conveyors pivotally mounted on said head piece, a variably inclined conveyor pivotally connected to said head piece and means mounted in said head piece for conveying material from said first mentioned conveyors to said variably inclined conveyor.

10. In a device of the class described, the combination of a head piece, opposed conveyors pivotally connected to said head piece, a motor operatively connected with said conveyors for driving the same, an auxiliary motor operatively connected in a manner to draw said conveyors to and from each other and means for carrying the material from said conveyors to a discharging point.

15. In a device of the class described, the combination of a superstructure, a carriage mounted thereon, a head piece adjustably suspended from said carriage, means for raising and lowering said head piece, opposed conveyors pivotally connected to said head piece, a variably inclined conveyor pivotally connected to said head piece, a hopper suspended from said superstructure and adapted to receive the material from

20. said inclined conveyor and means for conveying the material from said first mentioned conveyors to said variably inclined conveyor.

25. In a device of the class described, the combination of a bridge, a carriage designed to travel thereon, head piece adjustably sus-

30. pended from said carriage, a motor on said carriage for raising and lowering said head piece, opposed bucket conveyors pivotally mounted on said head piece, a motor mounted on said head piece for driving said conveyors, substantially as and for the purposes set forth.

35. In a device of the class described, the combination of a superstructure, a head piece adjustably suspended therefrom, a variably inclined conveyer pivotally connected to said head piece, opposed digging conveyors pivotally connected to said head piece, means for conveying the material from said digging conveyors to said variably inclined conveyors and means for operating said conveyors.

40. In a device of the class described, the combination of a plurality of opposed bucket conveyors and positive means for drawing said conveyors toward and from each other, said means comprising a screw-threaded bearing secured to the frame work of said conveyors, a screw-threaded shaft adapted to co-operate therewith, a worm gear on said shaft, a second shaft provided with a gear adapted to co-operate with said worm gear and means for driving said last mentioned shaft.

45. In a device of the class described, the combination of a plurality of opposed bucket conveyors and positive means for drawing said conveyors toward and from each other, said means comprising a plurality of cables so connected and operated by a drum as to draw said conveyors apart and a second set of cables so connected and operated as to draw said conveyors toward each other, substantially as described.

50. In witness whereof, I hereunto subscribe my name to this specification in the presence of two witnesses.

HAROLD K. SMITH.
